UNITED STATES PATENT OFFICE.

EDWARD R. HEWITT, OF RINGWOOD, NEW JERSEY, ASSIGNOR, BY MESNE ASSIGNMENTS, TO INTERNATIONAL MOTOR COMPANY, OF NEW YORK, N. Y., A CORPORATION OF DELAWARE.

AUTOMOBILE.

1,077,933.

Specification of Letters Patent.

Patented Nov. 4, 1913.

Application filed December 30, 1910. Serial No. 600,028.

To all whom it may concern:

Be it known that I, EDWARD R. HEWITT, a citizen of the United States, residing in Ringwood, county of Passaic, State of New Jersey, have invented certain new and useful Improvements in Automobiles, of which the following is a specification.

This invention relates to motor driven vehicles and especially to motor driven vehicles designed for trucking purposes, where the bodies overhang the prime mover or other parts, and so interfere that it is impossible to remove the motor for inspection or repair, without first removing the body or partially dismantling the truck.

The invention has for its object to improve generally the construction so as to facilitate the assembling of the motor and its radiator with the truck, or the dismantling of these parts without disturbing the other portions of the truck.

The improved structure includes a flanged sheet metal dash-board, which has a central opening through which the motor may be passed, and is provided with means for receiving the radiator and protecting it from injury.

While the invention may be applied in a variety of ways and in various combinations, one embodiment is illustrated in the accompanying drawings in which—

Figure 1 is a view in front elevation of the dash-board showing the central opening therein with the radiator indicated in dotted lines, and the motor illustrated in end elevation. Fig. 2 is a sectional view taken on the plane indicated by the line X X of Fig. 1, the radiator being indicated in dotted lines. Fig. 3 is a fragmentary view in side elevation of the forward end of a motor truck, parts being broken away in the interest of clearness, showing the motor in side elevation. Fig. 4 is a view in side elevation of a motor truck embodying the present invention.

In the drawings A represents a sheet metal dash-board having formed therethrough a central elongated opening B of an area sufficient to receive the motor. The dash-board A is formed about its outer periphery and around the opening B with flanges A' and B' struck up from the sheet metal, which act as stiffening members to prevent distortion. The dash-board A is further braced in its corners by angled members 1—1.

Securely riveted to the outer face of the dash-board A is a rectangular frame member C having substantially a similar outline with the opening B and surrounding the latter. The frame member C, as indicated in Figs. 60 1, 2 and 3 forms a housing for the radiator D. The housing C is formed from a channel beam and serves not only to protect the radiator D, but also to strengthen greatly the dash-board A.

The main channel members E, E of the truck and body are secured to the dash-board A by means of angled members or knees 2—2, and also by an angled portion of the web of the channel beams E, E, forming the 70 supporting structure for the dash-board. At the lower portion of the opening B, and symmetrically disposed at either side of the vertical central line, are two horizontal portions or seats B'', B'' formed by the flanges 75 B'. Channel members F, F are so secured to the dash-board A by knees 3—3 that their upper flanges form a continuous extension rearwardly of the seats B'', B'' of flange B. The channel members F, F are carried 80 at the inner or rear ends by suitable hanger bolts 4—4 and rigid braces 5—5 attached to the channel beam 6, which is transversely disposed to the main channel members E, E. The upper flanges of the channel members 85 F, F form a support for the motor or engine G, and also serve as slides or ways on which the engine may be slid into or out of position through the opening B.

The radiator D, which may be secured to the dash-board A by any suitable means, such as angled brackets 7—7, lies entirely within the rectangular channel member C and closes fully the opening B in the dash-board A.

Provision for cranking the engine may be made through an opening in the radiator in the usual manner. The upper inclined portions of the flange B' form a convenient support for one end of the engine hood 8.

It will be noted from the design disclosed, that the two side members E, E are tied together around the opening B both top and bottom, in a very rigid and substantial manner, and that the dash-board A forms the forward cross member of the frame sub-structure.

From the foregoing description of parts and their relations to each other, the method of assembling the engine on its supporting 110

members, will be understood to be as follows:—The engine supported by skid hooks or any other suitable means, is raised sufficiently to allow the fly-wheel to clear and pass through the opening B; the inner supporting lugs of the engine or those adjacent to the fly-wheel are allowed to rest on the upper flanges of the channel beams F, F, the outer lugs being canted upwardly; the engine is slid rearwardly through the opening B until the subeasing is free of the lower edge of the opening; the engine is lowered until all of its supporting lugs are allowed to rest on the channel beams F, F and the engine is pushed rearwardly to its position. The radiator D is then put in place and secured to the dash-board A by suitable bolts which pass through the dash-board and the brackets 7. Connection of the radiator D with the engine G to permit the circulation of the cooling fluid is made by the usual hose connection in any suitable manner. From the above description, it will be understood that the engine may be removed from the truck by reversing the assembling operation above outlined.

It is impossible to use a crane to lift out the motor from a heavy truck of ordinary construction, unless the body is first removed. The operation always entails considerable expense in loss of time and labor, which, owing to the frequent repairs necessary to the engine becomes a large item in the maintenance of the truck. By employing the improved construction herein illustrated, this loss of time and labor above referred to is eliminated and repairs may be accomplished in a much shorter time and at a lower cost.

40 While one particular embodiment of the present invention is herein shown and described, it will be evident that the construction is susceptible of modification in many respects.

45 What I claim is:—

1. In combination in a motor vehicle, a vertical dash-board at the forward end constituting a permanent dash and rigid permanent transverse connection between the forward ends of the frame, two longitudinal frame members with their forward ends attached to the dash and extending rearwardly, and a motor adapted to be supported at the forward ends of the frame members, 50 said dash having an opening adapted to permit the mounting and removal of said engine through the dash.

2. In combination in a motor driven vehicle, longitudinal frame members, a vertical dash-board constituting a permanent transverse connection between the forward ends of the longitudinal frame members and having an opening through which the driving motor is assembled, a radiator and a housing 60 for the radiator secured to the dash-board

and surrounding the opening in the dash-board.

3. In combination in a motor driven vehicle, a radiator and a dash-board having an opening through which the driving motor is moved horizontally to be mounted on or removed from the vehicle, said dash-board 70 constituting the forward cross member of said vehicle frame and surrounding and supporting the radiator.

4. In combination in an automobile, main frame members, two parallel longitudinal frame members between the main members and having a clear space extending between said members from the forward end, a transverse forward member interconnecting the forward ends of the longitudinal members and extending upward to form a permanent dash, and a motor adapted to be slid on and between said second longitudinal members, 80 said transverse member having an opening adapted to permit the passage of the complete motor longitudinally of the vehicle to and from the supporting frame members.

5. In combination in an automobile, longitudinal frame members spaced to support lateral extensions of a motor, a motor, a transverse braced frame at the adjacent end of the vehicle extending upward to form a permanent dash and having an opening 95 therein of a size sufficient to permit the horizontal passage of the motor, and a radiator adapted to be supported in said opening.

6. In an automobile, longitudinal frame members on either side, means connected with said frame members to removably support a motor between them at one end of the frame, a motor, a transverse member permanently attached to extreme forward ends of said longitudinal members and extending upward to form a rigid, transverse connection and to constitute also a permanent dashboard at the extreme end of the frame, a radiator, said transverse member having an opening of a size to permit the horizontal passage of the motor for mounting and demounting, and means to support the radiator detachably on said transverse member to close said opening when the motor is mounted on the vehicle.

7. In combination in a vehicle, longitudinal members, a permanent transverse member attached to the frame ends of said longitudinal members and constituting a rigid connection, as well as a permanent dashboard, a radiator, said transverse member having an opening, and means for securing said radiator detachably on said transverse member to cover the opening.

8. An automobile including a chassis 125 frame adapted to have the engine and associated parts mounted on the front portion thereof, a dash mounted in connection with said frame in front of the position for said engine and associated parts and consisting 130

of an upper portion and lateral downwardly extending portions so the engine and associated parts will be accessible from the front through said dash, and a water cooler mounted in connection with said dash so as to close the opening in the dash and be readily removable.

This specification signed and witnessed this 29 day of December, A. D., 1910.

EDWARD R. HEWITT.
